M. M. Dolmage - INVENTOR

UNITED STATES PATENT OFFICE.

MIHRAN M. DOLMAGE, OF WASHINGTON, DISTRICT OF COLUMBIA.

WIRELESS DUPLEX SIGNALING SYSTEM.

1,414,629.

Specification of Letters Patent. Patented May 2, 1922.

Application filed July 15, 1918. Serial No. 245,101.

To all whom it may concern:

Be it known that I, MIHRAN M. DOLMAGE, a citizen of the United States, residing at 825 Vermont Avenue NW, Washington, in the District of Columbia, have invented 5 in certain new and useful Improvements in Wireless Duplex Signaling Systems, of which the following is a specification.

This invention relates to a wireless duplex signaling system. Its object is to provide a system for the simultaneous transmission and reception of signals and in particular to provide means for two way wireless telephone communications.

10 To secure successful wireless duplex operation, it is necessary to render the receiving equipment free from the interference by the transmitting equipment at the same station. There are a number of systems available to the art at the present time for accomplishing this purpose, some depending upon 15 the use of two different frequencies for transmission and receiving, other systems dependent upon the use of a compensating antenna, etc. In all such cases, some approach is made to true duplex operation, but never accomplished absolutely. Where long 20 range wireless operation is concerned, the magnitude of the transmission current is so 25 enormously greater than that excited in the antenna by the received waves of low amplitude, that no real hope can be entertained to secure duplex operation by local compensating circuits of differential character, so far 30 as the reception of signals is concerned, even when a different frequency is used for receiving and for transmitting, and the receiving 35 circuit is sharply tuned for this purpose.

This invention utilizes voice operated circuit changing means which control the circuits of the duplex wireless system in such a way as to completely eliminate the reaction of the transmitted energy upon the receiving apparatus at the transmitting station. 40 Circuit changing means, voice controlled in their operation, have heretofore been disclosed. This invention differs, however, from most previous inventions in that it does not require the operation of a switch for putting 45 the transmitting apparatus into electrical connection with the antenna. In the system described herein, the transmitting

apparatus as well as the receiving apparatus at the wireless station are normally connected to the antenna. No part of a sentence 55 spoken into the transmitter at the wireless station is distorted or lost during the time interval required for establishing a condition for proper transmission, as in the systems previously disclosed by other inventors utilizing normally open transmitting circuits in combination with voice operated means for closing the transmitting circuits to the antenna. It is evident, that, in any 60 system of duplex operation, the voice controlled circuit changing means itself should be completely shielded from the effect of signals radiated by other wireless stations, also from static impulses or grinders which may reach the circuit changing means via the antenna. 65 If such shielding is not provided for, false operations would result. In the invention herein disclosed, the voice operated relay which controls the direction of transmission is connected to points of the same potential, under all conditions, for all waves 70 received by the antenna whether useful or interfering in character. In this respect the system herein disclosed is therefore completely free from all false operations of the 75 control relay.

A further important advantage of the system described herein consists in the utilization of devices for amplifying the controlling voice currents so that the operation of 80 the circuit changing means may be made of certain and positive character. The use of such amplifying devices has been indicated in conjunction with the particular duplex wireless circuit shown in attached drawings, 85 but it is clear that such devices may be used with any other wireless duplex signaling circuits, depending for their operation upon the utilization of voice operated circuit changing means. A practical solution is 90 shown in the utilization of a device of the type known as an "audion", which can be made to amplify alternating currents of both audio and radio frequencies into direct current. It then becomes possible to use direct current electromagnetic relays, which 95 usually can be made more sensitive than alternating current relays for the purpose of securing the proper transmitting and receiv-

ing relations in the duplex wireless system. In place of an "audion" any other device having similar characteristics, such as a kenotron (General Electric Review vol. XVIII, 5 page 156) or a pliotron (General Electric Review, vol. XVIII, page 327) may be used.

This invention is illustrated in its fundamental features in Fig. 1 and Fig. 2. A 10 modification of the arrangement shown on Fig. 1 is indicated on Fig. 2. Referring first to Fig. 1, 1 is an antenna for the simultaneous transmission and reception of signals. Antenna 1 includes two parallel branches which 15 are also in series with the primary of receiving transformer 18. One branch includes primary winding of coil 2 of automatic controlling circuit A and secondary winding of transformer 6. The other branch includes 20 primary winding of coil 3 of automatic controlling circuit A, and an artificial line comprising inductive resistance 4 and condenser 5. It is contemplated to have the artificial line balance very accurately the transmitting 25 circuit of the duplex system. This arrangement neutralizes completely the electromotive forces generated in the secondary windings of coils 2 and 3, on all received signals. Transformer 6 is connected to the plate circuit 30 of a vacuum tube modulator 7 (such as an audion or pliotron). The grid circuit of this same tube 7 is connected to condenser 8—which in turn is bridged by modulating transformer 9 and transformer 11. The primary winding of transformer 11 is connected 35 to a suitable source 12 of high frequency currents. The secondary windings of coils 2 and 3 are closed through condenser 13 which is bridged by the grid circuit of a 40 vacuum tube amplifier 14. The plate circuit of this same tube 14 is bridged by resistance 15, which in turn is bridged by relay 17 and condenser 16. The receiving of signals is obtained through transformer 18, 45 its secondary winding bridged by tuning condenser 19. Bridged around the tuning condenser is the vacuum tube amplifier 20 with its component grid, filament and plate circuits. The plate circuit of tube 20 is connected 50 through transformer 21 and tuning condenser 22 to a second vacuum tube detector 23 with its corresponding filament, grid and plate circuits. The plate circuit is closed through by resistance 24 and the usual 55 receiving telephone 26 and condenser 25. Fig. 2 is an alternative arrangement for that shown in elements 15, 16 and 17 of Fig. 1. In place of the alternating current relay 17, a direct current relay 27 is substituted. Element 60 14, when used in conjunction with the arrangement of Figure 2, is a device for rectifying and amplifying alternating currents, instead of being merely an amplifier which is the sole function it performs when used in

conjunction with the arrangement shown on 65 Figure 1. When radio frequency currents are being emitted, there will be, on account of the rectifying qualities of bulb 14, unidirectional impulses through relay 27, which would operate. To prevent the operation of this relay when the transmitter is not being spoken into, a direct current electromotive force is applied through an adjustable resistance, balancing to any degree that may be found desirable the unidirectional impulses through 70 relay 27. When, however, voice impulses are impressed upon the transmitter, the electrical balance above described will be destroyed, resulting in the operation of relay 27, which is the end desired. 80

In a circuit of the character outlined above, the following operation will obtain. High frequency currents generated by source 12, are amplified by tube 7 and then transmitted through transformer 6. These high frequency currents reach the antenna through coil 2 and are radiated by the antenna into space. These radio frequency currents also penetrate into coil 3 and balancing artificial circuit comprising the elements 4 and 5. 90 The electromotive forces generated in the secondary windings of coils 2 and 3 are cumulative in their effect and act upon the grid circuit of tube 14. Radio frequency currents, therefore, flow through condenser 95 16 and relay 17. They have no effect, however, upon relay 17, no more than sustained or non-modulated radio frequency currents received from distant points have any effect upon receiver 26. However, when transmitter 10 is spoken into, and a modulation secured in the amplitude of the high frequency currents generated by source 12, then the audio frequency variations of these high frequency currents will operate alternating 100 current relay 17. This relay operates during the time the transmitter is spoken into and short circuits tuning condenser 22, thereby preventing any of the transmitted audio frequency impulses from reaching receiver 110 26. This receiver therefore remains absolutely silent. On signals received by the antenna, on account of the electrical association of coils 2 and 3, in the manner shown, and as previously described, the two terminals of condenser 13 will be at the same potential. This result follows, since, by construction, on received signals the electrical impedance of artificial balancing circuit comprising elements 3, 4, and 5 is equal to 115 the impedance of the transmitting circuit comprising elements 2 and 6. The electromotive forces generated in the secondaries of coils 2 and 3 will consequently be equal and opposite in phase. Hence no high frequency current circulates, on received signals, in the circuit of the secondaries of coils 2 and 3. No high frequency currents nor 120 125

audio frequency modulations of such currents penetrate, therefore, into the grid circuit of vacuum tube amplifier 14. Therefore, the two terminals of relay 17, during receiving, are at the same potential. This relay, therefore, cannot operate on received signals. Relay 17 is not actuated, therefore, on receiving. Radio frequency currents reaching transformer 18 will therefore reach 10 their destination unhampered and the receiving will be obtained in full amplitude at receiver 28.

It is clear from the above description that this invention is not in any way limited to 15 any one particular type of wireless signaling system. What is characteristic of this system is the use of an auxiliary circuit, of a control relay in this auxiliary circuit actuated by audio frequency modulations of 20 the transmitted radio frequency currents, with balancing artificial circuit, substantially as described. Instead of using a control relay of alternating current type, I find it desirable in some cases to use a very sensitive 25 direct-current relay in association with a counterbalancing electromotive force, the above combination taking the place of the alternating current relay 17 and condenser 16.

30 What I claim is:

1. In a system for the transmission and the reception of wireless signals, an antenna, transmitting apparatus normally connected to said antenna, an auxiliary circuit, a device 35 for rectifying and amplifying alternating currents in said auxiliary circuit, a control relay associated with the aforesaid device responsive to the currents rectified and amplified by the aforesaid device, receiving apparatus normally connected to the antenna, and means under the control of the aforesaid relay rendering inoperative the receiving apparatus when said system is used for transmission.

45 2. In a system for the transmission and reception of wireless signals, an antenna, transmitting apparatus normally connected to said antenna, an auxiliary circuit, a second circuit balancing the transmitting circuit on receiving signals, a control relay in 50 said auxiliary circuit, receiving apparatus normally connected to the antenna, and means under the control of the aforesaid relay rendering inoperative the receiving apparatus when said system is used for transmission.

55 3. In a system for the transmission and reception of wireless signals, an antenna, transmitting apparatus normally connected to said antenna, an auxiliary circuit, a second circuit balancing the transmitting circuit on received signals, a device for rectifying and amplifying alternating currents 60 in said auxiliary circuit, a control relay re-

sponsive to the currents amplified and rectified by aforesaid device, receiving apparatus normally connected to the antenna, and means under the control of aforesaid relay rendering inoperative the receiving apparatus when said system is used for transmission. 65 70 75

4. In a system for the transmission and reception of wireless signals, an antenna, transmitting apparatus normally connected to said antenna, an auxiliary circuit, a second circuit balancing the transmitting circuit on received signals, means for connecting said auxiliary circuit with said transmitting circuit and said balancing circuit, a control relay connected to points of equal 80 potential for received energy in aforesaid auxiliary circuit, receiving apparatus normally connected to the antenna and means under the control of aforesaid relay rendering inoperative the receiving apparatus 85 when said system is used for transmission.

5. In a system for the transmission and reception of wireless signals, an antenna, transmitting apparatus normally connected to said antenna, an auxiliary circuit, a second circuit balancing the transmitting circuit, means for connecting said auxiliary circuit with said transmitting circuit and said balancing circuit, a device for rectifying and amplifying alternating currents 95 connected to points of equal potential on received signals in the aforesaid auxiliary circuit, a control relay associated with the aforesaid device responsive to the currents rectified and amplified by the aforesaid device, receiving apparatus normally connected to the antenna, and means under the control of the aforesaid relay rendering inoperative the receiving apparatus when said 100 system is used for transmission. 105

6. In a system for the transmission and reception of wireless signals, the combination of an antenna, transmitting apparatus normally connected to the antenna, receiving apparatus normally connected to the antenna, connections to a wire telephone system, with circuit changing means controlled directly by electric currents predominantly of audio frequency character and arranged to render inoperative the receiving 110 apparatus when said system is used for transmission. 115

7. In a system for the transmission and reception of wireless signals, the combination of an antenna, receiving apparatus, a source of radio frequency currents, connections to a wire telephone system, a modulator, a demodulating tube, circuit changing means controlled by the resulting demodulated currents and arranged to render inoperative the receiving apparatus when said 120 system is used for transmission. 125

8. In a system for the transmission and

reception of wireless signals, the combination of an antenna, transmitting apparatus normally connected to the antenna, receiving apparatus normally connected to the antenna, with voice controlled circuit changing means completely shielded from all foreign interfering waves received through the antenna and arranged to render inoperative

the receiving apparatus when said system is used for transmission.

In testimony whereof I affix my signature in presence of two witnesses.
